HOLE SPOTTER FOR COLLARING DRILL HOLES

Charles A. Hirschberg, Mountain Lakes, N. J., assignor to Worthington Pump and Machinery Corporation, New York, N. Y., a corporation of Virginia

Application May 31, 1933, Serial No. 673,647

4 Claims. (Cl. 255—45)

This invention relates to rock drilling and more particularly to a hole spotter for collaring drill holes.

An object of the present invention is to provide a hole spotter for collaring drill holes embodying a drill bar engaging member for steadyng the drill bar during the spotting or starting of a drill hole, which device embodies means for ready and secure attachment to a percussive rock drill and is so constructed that after a hole has been spotted it may be folded or moved out of the way of the drill during the finishing of the drill hole.

With these and other objects in view as may appear from the accompanying specifications, the invention consists of various features of construction and combination of parts, which will be first described in connection with the accompanying drawings showing a hole spotter for collaring drill holes of the preferred form embodying the invention, and the features forming the invention will be specifically pointed out in the claims.

In the drawings:

Fig. 1 is a side elevation of the improved hole spotter showing the same applied to a percussive rock drill.

Fig. 2 is an end elevation of the hole spotter.

Fig. 3 is a side elevation of the hole spotter.

Fig. 4 is a detail cross section through the hole spotter taken on the line 4—4 of Figure 2.

Fig. 5 is a detail perspective view of the hole spotter showing the same in a partly open position.

Referring more particularly to the drawings, a percussive or pneumatic rock drill of any approved type is shown at A in Figure 1 of the drawings. While in Figure 1 a drill of the pneumatic feed type is illustrated, it is to be understood that the improved hole spotter may be used in connection with any suitable type of percussive tool without departing from the spirit of this invention.

The percussive tool A has a drill bar B carried thereby and as shown in Figure 1, the drill bar is in position for the starting of a drill hole in the rock or other substance C.

When starting a drill hole in rock particularly when the surface is irregular, the drill bar B has a tendency to oscillate or "wobble", rendering it difficult to spot a hole and requiring, in normal operation, a driller's assistant to hold the drill bar B steady until the drill hole is started.

The present invention embodies a hole spotter for attachment to the percussive drill or tool which will engage the drill bar B adjacent to the

bit for holding the drill bar steady to permit the starting or collaring of the drill hole without requiring the use of the driller's assistant.

In the preferred form of the invention shown in Figures 1 to 5 inclusive, the hole spotter comprises an attaching body 1 which has an opening 2 extending therethrough. The opening 2 receives a stud 3 formed on the cap 4 and a nut 5 is provided for securely attaching the carrying or attaching body 1 to the cap 4. The cap 4 forms the end of the feed cylinder 6 of the pneumatic feed mechanism of the percussive tool construction A. A plate 7 is attached to the body 1 and is adapted to engage the cylinder structure 6 to prevent turning or rotary movement of the body 1.

A supporting rod 8 is rotatably carried by the supporting body 1 and it rotates within the body 1. The ends 9 of the supporting rod 8, which project beyond the side edges of the body 1 are flat as clearly shown in Figures 3 and 5 of the drawings and they have drill bar engaging members 10 and 11, pivotally connected to these flattened ends by means of suitable pivot pins 12. The provision of the pivot pins 12 and the rotary mounting of the rod 8 permits the drill bar engaging members 10 and 11 to move in a universal manner with respect to the body 1 so as to permit them to be moved downwardly and outwardly into the position assumed by the member 11 in Figure 5 of the drawings, after the hole has been spotted or started.

The members 10 and 11 are provided with cut out portions 14 in their inner facing edges which cutout portions engage a rib 15 formed on the body 1 so as to prevent any pivotal or rocking movement of the members 10 and 11 with respect to the body 1 when the members 10 and 11 are in drill bar engaging position.

The members 10 and 11 are provided with semi-cylindrical cutout portions near their outer free ends which are of sufficient size to firmly grip the drill bar B and hold it against oscillatory or "wobbling" movement, when the members 10 and 11 are in their upright drill bar engaging position.

Suitable means are provided for locking the members 10 and 11 in their upright drill bar engaging position and while a specific type of locking means is illustrated in the drawings, and hereinafter described, it is to be understood that any suitable type of locking means may be employed without departing from the spirit of the present invention.

The locking means illustrated in the drawings comprises a substantially U-shaped locking bar

- 17 which is slidably carried by the member 11, being guided in its sliding movement by suitable guide pins 18. Locking pins 19 are carried by the member 10 and are engaged by the hooks 20 on the ends of the U-shaped locking bar 17 when the latter is in locking position. A suitable stop pin 21 is provided for limiting the downward movement of the U-shaped locking bar 17. A tightening or clamp screw 22 is carried by the member 17 and its inner end clamps against the facing side of the member 11 for securely tightening the hooks 20 on the locking pins 19 to lock the members 10 and 11 in their upright drill bar engaging position.
- 15 As shown in Figures 4 and 5 of the drawings, the supporting rod 8 may be cut out as shown at 26 to prevent interference between the rod and the stud or stem 3 and permit unimpeded rotation of the rod 8.
- 20 In operation, when it is desired to start a drill hole, the drill hole spotter is attached to the percussive tool or drill A by mounting the body 1 upon the stud 3 and tightly clamping it in place against the end of the cap 4 by means of the nut 5. After the hole spotter has been securely clamped to the percussive tool rig, the members 10 and 11 are swung upwardly until the drill bar is engaged in the cutout portions 16, and the locking bar 17 is then swung on its supporting pin 18 until the hooks 20 engage the locking pins 19 after which the locking or clamp screw 22 is tightened to securely lock the members 10 and 11 in their drill bar engaging position, for holding the end of the drill bar steady to permit spotting or collaring of the drill hole. After the drill hole has been started, and has gained sufficient depth to act as a steady medium upon the cutting end of the drill bar, the clamp screw 22 is loosened, and the locking bar 17 is swung upwardly and outwardly to disconnect the members 10 and 11. These members are then moved outwardly and downwardly, and if necessary either forwardly or rearwardly by rotating the pins 12 or rod 8 so that they will be down out of the way of the chuck end of the percussive tool as it approaches the surface which is being drilled.
- From the foregoing description taken in connection with the accompanying drawings, it will be apparent that a hole spotter for collaring drill holes has been provided, which is simple in construction, may be attached to any approved type of rock drilling rig or percussive tool rig and will serve to hold the drill bit end of the drill bar steady, against vibration or "wobbling" during the starting or spotting of a drill hole, one which will consequently eliminate the use of an assistant driller for this purpose, as well as a device which can be quickly swung out of position after
- the drill hole has reached sufficient depth to render further use of the spotter unnecessary.
- It will be understood that the invention is not to be limited to the specific construction or arrangement of parts shown but that they may be widely modified within the invention as defined by the claims. 5
- What is claimed is:
1. In a hole spotter for collaring drill holes, a pair of drill bar guiding members, a support for said members, said members pivotally connected to said support to permit them to be swung away from a drill bar, a universal connection between said members and said support, means for locking said members in drill bar guiding position, 10 and means for preventing rotary movement of said support relative to a drill bar.
2. The combination with a percussive drill, a drill bar, and a feeding mechanism for the drill, of a hole spotter for collaring drill holes including a support, means for attaching said support to said feeding mechanism, a plurality of drill bar guiding members pivotally carried by said support for movement into and out of drill bar guiding position and means connecting said members to said support to permit universal swinging movement of the members relative to said support. 20
- 25
3. The combination with a percussive drill, a drill bar and a feeding mechanism for the drill of a hole spotter for collaring drill holes including a support, means for attaching said support to said feeding mechanism, a plurality of drill bar guiding members pivotally carried by said support for movement into and out of drill bar guiding position, means connecting said members to said support to permit universal swinging movement of the members relative to the support, a rib on said support, said members provided with recesses to receive said rib to prevent movement of the members relative to the support when in drill bar engaging position. 30
- 35
4. The combination with a percussive drill, a drill bar and a feeding mechanism for the drill, of a hole spotter for collaring drill holes including a support, means for attaching said support to said feeding mechanism, a plurality of drill bar guiding members pivotally carried by said support for movement into and out of drill guiding position, means connecting said members to said support to permit universal swinging movement of the members relative to the support, a rib on said support, said members provided with recesses to receive said rib to prevent movement of the members relative to the support when in 40
- 45
- 50
- 55
- drill bar engaging position, and means for locking said members in or out of drill bar guiding position.

CHARLES A. HIRSCHBERG.
